PICTURE FRAME OR THE LIKE

Violet H. Mueller and Harry E. Mueller, both of 604 N. Hamilton, Salem, Ill.

Filed May 31, 1963, Ser. No. 75,144

Term of patent 3½ years

(Cl. D29—20)

FIG.1

We claim:

The ornamental design for a picture frame or the like, substantially as shown and described.
